United States Patent Office

Des. 185,945
Patented Aug. 18, 1959

185,945

WATER SPRAY GUN

Jules Rosenkranz, New York, N.Y., assignor to Lafayette
Brass Mfg. Co., Inc., a corporation of New York

Application May 12, 1958, Serial No. 50,845

Term of patent 14 years

(Cl. D91—1)

Fig. 1 is a perspective view of a water spray gun looking toward the front thereof; and

Fig. 2 is a perspective view of a water spray gun looking toward the rear thereof.

I claim:

The ornamental design for a water spray gun, substantially as shown.
